DESIGN FOR A DUTCH OVEN

Robert B. Wemyss, Louisville, Ky., assignor to Reynolds Metals Company, Richmond, Va., a corporation of Delaware

Application March 2, 1946, Serial No. 127,056

Term of patent 3½ years

(Cl. D44—1)

To all whom it may concern:

Be it known that Robert B. Wemyss, a citizen of the United States, residing in Louisville, county of Jefferson, State of Kentucky, has invented a new, original, and ornamental Design for Dutch Oven, of which the following is a specification, reference being had to the accompanying drawing, forming part thereof, wherein—

Fig. 1 is a top plan view of a dutch oven, showing my new design;

Fig. 2 is a perspective view thereof; and

Fig. 3 is a cross-section through the handle on line 3—3 of Fig. 2.

I claim:

The ornamental design for a Dutch oven, as shown.

ROBERT B. WEMYSS.
